UNITED STATES PATENT OFFICE.

WILLIAM P. CANTWELL, OF LIMA, OHIO.

MAUSOLEUM.

1,207,855.

Specification of Letters Patent. Patented Dec. 12, 1916.

Application filed January 19, 1916. Serial No. 72,978.

To all whom it may concern:

Be it known that I, WILLIAM P. CANTWELL, a citizen of the United States, residing at Lima, in the county of Allen and State of Ohio, have invented certain new and useful Improvements in Mausoleums, of which the following is a specification.

My invention relates to improvements in mausoleums wherein crypts or catacombs are preferably arranged in tiers or rows, so that access may be had to them by a corridor or passage.

An important object of the invention is to improve in general the construction of mausoleums of the above mentioned character, with a view of simplifying the same and rendering them highly efficient in fulfilling their function.

A further object of the invention is to provide simple and reliable means to thoroughly ventilate the walls of the building of the mausoleum.

A further object of the invention is to provide individual means for thoroughly ventilating each crypt or catacomb and discharging gases to the atmosphere exteriorly of the mausoleum, each crypt or catacomb having no communication with the other crypt or crypts.

A further object of the invention is to provide individual means to thoroughly drain each crypt or catacomb, without establishing communication between two or more of the crypts.

A further object of the invention is to provide means for conducting the gases from the crypts or catacombs through the top air chamber or attic of the construction, to the atmosphere without discharging the same into the top air chamber or attic.

A further object of the invention is to provide separate means for thoroughly ventilating the corridors of the mausoleum.

Other objects and advantages of the invention will be apparent during the course of the following description.

In the accompanying drawings forming a part of this specification and in which like numerals are employed to designate like parts throughout the same, Figure 1 is a vertical transverse sectional view through one-half of a mausoleum embodying my invention, Fig. 2 is a transverse sectional view taken on line 2-2 of Fig. 1, Fig. 3 is a horizontal sectional view taken on line 3-3

of Fig. 2; and, Fig. 4 is a perspective view of a crypt, showing the interior thereof.

In the drawings, wherein for the purpose of illustration is shown a preferred embodiment of my invention, the numeral 5 designates a preferably rectangular building or shell, constituting the body portion of the mausoleum. This body portion or shell embodies a corridor 6, having of course a suitable door and window or windows, if desired. The shell embodies a bottom air chamber or basement section 7 having air inlet openings 8 preferably covered by sections of screening 9, of a suitable mesh. Arranged beneath the corridor 6 is a second bottom or basement air chamber 10, having air inlet opening or openings 11 covered by sections of screening material 12 of a suitable mesh. The corridor has its floor 13 provided with a suitable number of opening or openings 14 establishing communication between the corridor and the air chamber 10, such opening being covered by a grate 15 or the like, of any well known or preferred construction.

Particular attention is called to the fact that the crypt bottom air chamber 7 has no communication with the corridor bottom air chamber 10. Formed in the top of the shell 5 is a crypt top air chamber or attic 16. Arranged to one side of the top chamber 16 is a top corridor air chamber 17, having opening or openings 18, communicating with the top of the corridor 5 and preferably covered with a section of screening material 19. Particular attention is called to the fact that the top chamber 16 has no communication with the top chamber 17. The corridor top air chamber has an air outlet 20, communicating with the atmosphere, as shown.

The numeral 21 designates crypts or catacombs, preferably arranged in vertical tiers or rows. The details of construction of each of these crypts will be given hereinafter. As clearly illustrated in Fig. 3, means are provided to ventilate the space between the crypts and the adjacent walls of the casing 5, for maintaining the crypts in a properly dry condition. Such means preferably comprises hollow tiles 22, as clearly shown in Fig. 1. These tiles form flues 23, the lower ends of which communicate with horizontal air inlet passages 24, while their upper ends communicate with the crypt top air chamber 16. The chamber

16 is provided with an outlet opening 25, preferably arranged adjacent the flues 23 and discharging into the atmosphere thus affording ventilation for the chamber 16. 5 The opening or openings 25 are preferably spanned by a section of screening material 26.

10 The crypts 21 are arranged in vertical tiers or rows, as shown, and each crypt comprises a substantially horizontal bottom 26, a top wall 27, side walls 28 and a closed rear wall 29, while the front end wall of the crypt, arranged adjacent the corridor 5 is open, but may be closed and sealed by means 15 of a door or slab 30, secured therein by any suitable means. It is obvious that to save space and economize in the construction of the building, and the crypts being arranged in vertical and horizontal rows, can have 20 their side walls, tops and bottoms in common with each other, while the invention is in no sense restricted to this construction, it being sufficient that no one crypt or catacomb has a communication with the other 25 crypt or catacomb or with the corridor to permit of the escape of gases therein.

It is an important feature of my invention to provide for the proper ventilation of each crypt or catacomb and discharge the 30 gases therefrom to the atmosphere, without introducing them into any other crypt or into the corridor. To accomplish this, I provide a pair of air inlet flues 31, having their lower ends communicating with the 35 bottom air chamber 7 and their upper ends discharging into the corresponding crypt 21, preferably adjacent the bottom, at one side thereof, and near its ends. The location of these air inlet flues is important, since as the 40 casket or coffin is arranged within the crypt the air will discharge therein and contact with the opposite ends of the casket or coffin thus causing it to circulate upwardly and inwardly about the casket, toward a centrally 45 arranged outlet opening, designated by the numeral 32. The outlet opening 32 leads into the crypt 21, through its side wall upon the opposite side thereof from the inlet openings 31 thus causing the ventilating air to 50 completely circulate about the casket and travel the maximum distance before discharging from the crypt. The spaced inlet openings in the crypts in each vertical tier or row are preferably formed through one 55 vertical common side wall while the outlet openings therefor are preferably formed through the opposite common vertical wall, with the inlet openings of the next row of crypts.

60 As clearly shown in Fig. 1, the numeral 33 designates a ventilator arranged within the crypt upper air chamber 16 but having no communication therewith. This ventilator has an upper reduced portion 34 passing through an opening 35 in the top wall 36

and discharges to the atmosphere. The ventilator is preferably provided with a cover or hood 37. The lower large end of the ventilator 33 contacts with the top wall of the top wall 27 and has an air tight joint therewith. The air outlet openings 32, preferably of two sets of vertical rows of crypts discharge into the ventilator 33 upon opposite sides thereof while it is of course understood that the invention is in no sense restricted to this precise arrangement. The particular advantage of this construction is that the gases from the individual crypts are drawn by the ventilator 33 and discharged to the atmosphere without being 70 able to pass into other crypts, into the attic or upper air chamber or chambers, or, into the corridor, whereby the building as a whole is maintained in a highly sanitary condition. 75

The bottom wall 26 of each crypt 27 has 80 its upper surface provided with a preferably flat triangular portion 38 decreasing in diameter rearwardly and inclined downwardly toward its rear reduced end. Upon opposite sides of the triangular portion 38 are 85 triangular portions 39, increasing in width rearwardly and inclined inwardly toward the portion 38 thus providing means whereby any liquid accumulating within the crypt will be conducted toward a rear end thereof 90 and discharge into a drain pipe 40. This drain pipe is preferably connected with a common drain pipe 41 which may discharge at any desired remote point. 95

In the use of the mausoleum, when it is 100 desired to inter a body therein, the door or slab 30 of the selected crypt 31 is removed and the casket or coffin containing the body is placed therein. I prefer to remove the lid of the casket or coffin or retain it partly 105 raised or elevated to provide ventilation for the corpse and I also preferably provide openings or holes in the bottom of the casket or coffin so that any liquid may freely drain therefrom through the bottom of the crypt 110 and be conducted through the same by the drain pipe as above explained. 115

Means are provided to dry the air or deprive it of substantially all of its moisture before entering the bottom air chamber 7. 120 This dry air passes up through the inlet flues 31 and discharges into the crypt at its bottom adjacent the ends of the casket. The air is deflected upwardly and inwardly about the casket, and caused to circulate transversely thereof to find its way to the outlet flue 32 disposed upon the opposite side of the crypt and arranged centrally with relation thereto. This air, which takes up the 125 gases in the crypt, discharges with it from the flue 32 into the ventilator 33 and thence passes to the atmosphere. In this manner the corpse is maintained thoroughly dry and decomposition is prevented, and the corpse gradually dries out, and remains in this con- 130

dition practically indefinitely. While the ventilation is going on in any suitable number of crypt or crypts, an entirely separate and independent ventilation takes place between the walls of the building and the crypts, through the flues 22 and within the upper air chambers 16 and the atmosphere through openings 25. Separate ventilation also occurs within the corridor 5, the air passing from the lower chamber 10 into the bottom of the corridor and discharging through the top thereof through the air chamber 17 and through the opening 20 to the atmosphere.

15 It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

25 1. In a mausoleum of the character described, a building casing, a bottom air chamber arranged in the lower portion thereof, a top air chamber arranged in the upper portion thereof, a set of noncommunicating crypts arranged between the bottom air chamber and the top air chamber, a ventilator arranged within the top air chamber and discharging exteriorly thereof to the atmosphere, means providing individual air inlets for each crypt, the air inlets leading into each crypt near its bottom and near its opposite ends upon one side thereof and having communication with the bottom air chamber, and means providing an individual air outlet for each crypt, the air outlet leading into the opposite side of the crypt near its top and spaced a substantial distance from the opposite ends thereof and having communication with the interior of the ventilator.

2. In a mausoleum of the character described, a building casing, a set of crypts arranged therein, a crypt bottom air chamber disposed beneath the crypts and having separate means of communication with each crypt, a crypt top air chamber disposed above the crypts and having no communication therewith and having communication with the atmosphere, an outlet conduit having no communication with the crypt top air chamber and having separate means of communication with each crypt, a corridor formed within the building casing to provide access to the crypts, a corridor bottom air chamber disposed beneath the corridor and having no communication with the crypt bottom air chamber and having communication with the atmosphere and also having communication with the corridor, and a corridor top air chamber having no

communication with the crypt top air chamber and having communication with the atmosphere and having communication with the corridor.

3. In a mausoleum of the character described, a building casing, a bottom air chamber arranged in the lower portion thereof, a top air chamber arranged in the upper portion thereof, a set of non-communicating crypts arranged between the bottom air chamber and top air chamber, a ventilator arranged within the top air chamber and having no communication therewith and discharging exteriorly thereof to the atmosphere, means providing an individual air inlet flue for each crypt having communication with the bottom air chamber, and means providing an individual air outlet flue for each crypt having communication with the interior of the ventilator.

4. In a mausoleum of the character described, a building casing, a bottom air chamber arranged in the lower portion thereof, a top air chamber arranged in the upper portion thereof, a set of non-communicating crypts arranged between the bottom air chamber and the top air chamber, a ventilator arranged within the top air chamber and having no communication therewith and discharging exteriorly thereof to the atmosphere, means providing an individual air inlet flue for each crypt which has communication with the bottom air chamber, means providing an individual air outlet flue for each crypt which has communication with the interior of the ventilator, and a set of ventilating conduits arranged between the exterior of the crypts and the adjacent wall of the building casing and communicating near their ends with the atmosphere.

5. In a mausoleum of the character described, a building casing having a corridor, a corridor bottom air chamber arranged beneath the corridor and having means of communication therewith, a corridor top air chamber arranged above the corridor and having means of communication therewith, a bottom crypt air chamber arranged adjacent the corridor bottom air chamber and having no communication therewith, a crypt top air chamber arranged adjacent the corridor top air chamber and having no communication therewith, a set of non-communicating crypts arranged between the crypt bottom and top air chambers, a ventilator arranged between the crypt top air chamber and having no communication therewith and discharging exteriorly thereof to the atmosphere, means providing an individual air inlet flue for each crypt which has communication with the crypt bottom air chamber, means providing an individual air outlet flue for each crypt which has communication with the interior of the ventilator, and a set of ventilating conduits arranged between the

exterior of the crypts and the adjacent wall of the building casing, and communicating near their ends with the atmosphere.

6. In a mausoleum of the character described, a building casing, a set of crypts arranged therein, a crypt bottom air chamber disposed beneath the crypts and having separate means of communication with each crypt, a crypt top air chamber disposed above the crypts and having no communication therewith and having communication with the atmosphere, air circulating means arranged between the closed ends of the crypts and the wall of the building casing and communicating at its lower end with the atmosphere and at its upper end with the crypt top air chamber, outlet means for each

crypt having communication with the atmosphere and having no communication with the top crypt air chamber, a corridor 20 formed within the building casing to provide access to the crypts, air supply means leading into the bottom of the corridor and having no communication with the bottom crypt air chamber, and air outlet means leading 25 into the top of the corridor and having no communication with the crypt top air chamber.

In testimony whereof I affix my signature in presence of two witnesses.

WILLIAM P. CANTWELL.
